REVERSIBLE WINDER FOR STRIP FILM

Hale G. Smith, Rockville Centre, N. Y., assignor
to Fairchild Camera and Instrument Corporation,
Jamaica, N. Y., a corporation of Delaware

Application January 21, 1947, Serial No. 723,329

8 Claims. (Cl. 242—55)

1

This invention relates to apparatus for winding exposed strip film back and forth between two reels submerged in a processing bath.

In the processing of substantial lengths of strip film, for example, 50 or 100 foot or more reels of motion picture film, apparatus has been available for mounting full and empty reels in a developer or fixer tank with mechanism for rotating the reels first in one direction and then in the opposite direction to wind the film from one reel to another and back again while the film is submerged in the developing or fixing bath as the case may be. Such apparatus, however, has not been universally satisfactory by reason of its structural complexity, costliness and the necessity for use of an expensive reversing electric motor. Then too, the reversing action in many of these devices is not positive in nature and it occasionally occurs that the film strip is reversed before the end of one reeling operation is reached with the result that the film is non-uniformly processed in the bath. For example, where a reversible motor is used, the apparatus is so arranged that when a certain degree of tension is exerted on the film, the motor automatically reverses. If, however, accidental tension of sufficient value is created during the winding operation, the motor accordingly reverses before the end of the winding operation resulting, of course, in non-uniform processing.

Accordingly, it is among the objects of this invention to provide a structurally simple, inexpensive, positive-acting reversible winder for strip film which overcomes the above-noted objections. Other objects will be in part apparent and in part pointed out hereinafter.

In accordance with one form of my invention, an electric motor is pivotally mounted on a panel and has its armature connected through suitable reduction gearing to a drive gear which meshes with an idler or planetary carried by an arm or yoke freely mounted on the shaft of the drive gear. The idler is adapted to mesh with one or another of two gears respectively fastened to shafts which carry at their ends film reels so that as one of such shafts is rotated, film may be unwound from the reel of the other shaft to the reel on the driven shaft. To effect the reversing at the end of the winding operation, the idler gear climbs over the gear with which it is in mesh and it is carried over into mesh with the opposite reel gear by pivoting the motor about its mount, a spring being provided to return the motor to a central position after the gear mesh has been changed.

2

One form of my invention is illustratively shown in the drawing, wherein,

Figure 1 is a vertical section of the device taken along the line 1—1 of Fig. 2.

Figure 2 is a top plan view of the device.

Figure 3 is a staggered section taken along the line 3—3 of Fig. 1, and

Figure 4 is an enlarged horizontal section taken along the line 4—4 of Fig. 1.

Similar reference characters refer to similar parts throughout several views of the drawing.

Referring first to Fig. 1, my reversible strip film winder is generally indicated at 10, and in general comprises a fractional horsepower unidirectional electric motor 11, connected by means of a gear reduction generally indicated at 12, to a main drive gear 13. This gear 13 alternately drives one or the other of a pair of reel gears 14 and 15 to rotate one or another of a pair of reels 16 and 17 disposed within a tank 18 in such a manner as to directly expose all of the film held by the reel to the action of whatever solution is contained in the tank, all as will be described in detail hereinafter. The film strip is thus wound from one reel to another and back again over and over again as long as is necessary to process the film.

As is more clearly shown in Fig. 3, the motor 11 is attached to a pair of brackets 19, pivotally mounted on a post 20, fastened in any suitable manner to a panel or table 21. This table is provided with a downwardly extending peripheral flange 22, adapted closely to fit the top edge of tank 18, so as to be in light-tight relation thereto when placed on the tank. A flat spring 23 has its lower end 23a fastened to a boss 19a mounted on lower bracket 19, the upper end 23b of this spring lying within the yoke portion 24a of a collar 24, adjustably mounted on post 20 whereon it may be held in adjustment by a set screw 24b. Spring 23 accordingly biases motor 11 to a central position between reels 16 and 17 as shown in Figs. 1 and 2.

To the lower end of the armature shaft of the motor is fastened a pinion 25 which meshes with a gear 26 rotatably mounted on a stud shaft (not shown) carried by a downwardly extending boss 27 of the motor housing. Fastened to or integral with gear 26, is a pinion 28 which meshes with a gear 29 rotatably mounted on a shaft 30, the upper end of which is secured in any suitable manner in a boss 31 or the like, integral with or secured to the housing of motor 11. By any suitable means gear 29 is connected to driving gear 13 also freely rotatable on shaft 30. It may now

be seen that when motor 11 is energized, main driving gear 13 is rotated by the reduction train comprising pinion 25, gear 26, pinion 28 and gear 29.

Referring back to Figure 1, shaft 30 has freely mounted thereon a pair of spaced arms 33 and 34 on opposite sides of main driving gear 13, the free ends of these arms rotatably supporting in any suitable manner an idler or planetary gear 35 which is in constant mesh with main driving gear 13. This gear 35 is adapted alternately to mesh with reel gears 14 and 15 in a manner to be described.

Reel gear 14 is fastened to the top of a shaft 36 as by a pin 37 extending through the gear hub 14a. Shaft 36 extends downwardly through a flanged collar 38 carried by panel 21 and through the panel to a point adjacent the bottom of tank 18. The lower end of shaft 36 is suitably formed to detachably carry film reel 16, so that when the shaft is rotated, so also is the reel. Reel gear 15 is attached to the upper end of a shaft 39 which is identical in structure and mounting to shaft 36 so as detachably to support on its lower end film reel 17. It may now be seen that if reel 17 is loaded with film and the loose end of the film is attached to reel 16, the film will be wound from reel 17 to reel 16 when gear 35 is in its Fig. 1 or Fig. 2 position.

When, however, all of the film has been wound from reel 17 to reel 16, it being noted that the other end of the film is securely attached to reel 17, idler or planetary gear 35 can no longer drive reel gear 14 as the gear is held against rotation by the film end attached to reel 17. Main driving gear 13, however, continues to rotate with the result that gear 35 (Fig. 2) climbs counter-clockwise about reel gear 14 forcing motor 11 and the reduction gearing 12 fastened thereto, clockwise about post 20 against the bias of spring 23 until the planetary gear has climbed past a line extending through the axes of reel shaft 36 and gear shaft 39. The gear 35 will continue to climb counter-clockwise around reel gear 14 until spring 23 has returned to the central position shown, at which time it will unmesh from reel gear 14 and be carried around shaft 30 together with arms 33 and 34 until it meshes with reel gear 15.

By referring to Fig. 4, the action of gear 35 climbing around reel gear 14 with the resulting deflection of spring 23, may be observed, the position of arms 33 and 34 and also gear 35 with respect to reel gear 15, being shown in dot-dash lines. Of course, when planetary gear 35 meshes with the other reel gear 15, it starts to drive this reel gear clockwise as viewed in Fig. 4, so that film F starts to wind on reel 17 from reel 16, the latter reel of course, now being freely rotatable. The tension of spring 23 may be adjusted by adjusting the position of collar 24 on post 20 to shorten or lengthen the effective length of the spring. The tension of this spring, however, is preferably so set that only the substantial film tension resulting from the film being completely unwound from one reel can overcome the tension of the spring to deflect it and permit the idler gear to climb over and unmesh from that one of the reel gears with which it was in mesh.

The relationship between planetary gear 35 and reel gear 15 (Fig. 4) is substantially the same as between the planetary gear and reel gear 14. In other words, when gear 35 is rotating counter-clockwise as viewed in Fig. 4, reel gear 15 is driven clockwise until the film F is completely wound

thereon so that the empty reel 16 can no longer rotate. Under such condition, of course, the now full reel 17 can no longer rotate and accordingly gear 35 starts to climb counter-clockwise as viewed in Fig. 4, around reel gear 15 forcing motor 11 and the attached reduction gearing to the right, to deflect spring 23, oppositely from the position shown in this figure. Planetary gear 35, of course, continues to climb around reel gear 15, until it is completely clear, i. e., out of mesh of the reel gear so that it can be carried around with arms 33 and 34 until it again meshes with reel gear 14.

From the above, it may now be seen that reel gears 14 and 15 and accordingly, their respective reels 16 and 17, are always driven clockwise by gear 35 as viewed in Fig. 4. Thus, as the planetary gear shuttles from one reel gear to the other, the respective reels are driven so that the film strip in its entirety is passed back and forth between the reels with all portions of the strip accordingly being uniformly processed. In this connection, it might be well to note that the tension of spring 23 can be of such a value as to be well in excess of any accidental tension that might occur during the passage of the film from one reel to another. It accordingly follows that the reversing action is positive in nature and can occur only when the film is completely unwound from one of the reels.

Thus it may be seen that I have provided a reversible winder for strip film which attains the several objects set forth hereinabove in a thoroughly practical and efficient manner.

I claim:

1. In a reversible winder for strip film, the combination of, a pair of reels adapted to have fastened respectively thereto the opposite ends of a film strip, means rotatably mounting said reels in spaced relation whereby the film strip may be wound from one reel to the other and back again, a pair of elements attached respectively to said reels and adapted to be alternately driven to rotate said reels, unidirectional driving means, means resiliently mounting said driving means, a rotatable element constantly driven by said driving means, and means mounting said rotatable element for movement into driving relation with one or the other of said reel rotating elements in response to tension of the film strip.

2. In a reversible winder for strip film, the combination of, a pair of reels adapted to have fastened respectively thereto the opposite ends of a film strip, means rotatably mounting said reels in spaced relation whereby the film strip may be wound from one reel to the other and back again, a pair of gears attached respectively to said reels and adapted to be alternately driven to rotate said reels, unidirectional driving means including a driving gear, means resiliently mounting said driving means, a planetary gear in constant mesh with said driving gear, means mounting said planetary gear for movement into mesh with one or the other of said reel gears, and means responsive to tension of the film strip for moving said planetary gear out of mesh with one of said reel gears and into mesh with the other of said reel gears.

3. Apparatus according to claim 2 wherein the driving means includes an electric motor, means mounting said motor for bodily movement relative to said reel gears, and spring means tending to hold said motor on a line midway of said reel gears.

4. In a reversible winder for strip film, the

combination of a base, a pair of film reels rotatably mounted on said base, a drive gear attached to each of said reels, driving means including a shaft and a driving gear mounted on said shaft, means resiliently mounting said driving means for lateral bodily movement relative to said reels, and a planetary gear assembly comprising a planetary gear and at least one arm rotatably connected to said shaft and supporting said planetary gear in constant mesh with said driving gear, said planetary gear meshing alternately with said reel drive gears to rotate them and accordingly said reels alternately in the same direction, whereby when that one of said reel gears in mesh with said planetary gear is constrained against rotation, said planetary gear climbs around said constrained reel gear and causes said driving means to move relative to said constrained gear until said planetary gear and said constrained gear become unmeshed, whereafter said planetary gear travels around said driving gear until it meshes with the other reel gear.

5. Apparatus according to claim 4 wherein said base has a post secured thereto on which the driving means is pivotally mounted, and spring means are provided tending to maintain said driving means on a line midway of said reel gears.

6. Apparatus according to claim 4 wherein the driving means comprises a unidirectional electric motor, and reduction gearing by which said driving gear is driven.

7. Apparatus according to claim 4 wherein the base comprises a flat plate having a downwardly depending peripheral flange adapted to fit about the rim of a film processing tank, the film reels also depending downwardly of the base plate so as to be disposed within said tank.

8. In apparatus of the character described wherein a strip to be processed is carried in coils on a pair of juxtaposed reels each mounted on a shaft with one end of the strip fixed to one

reel and the other end fixed to the other and wherein during processing the strip alternately and repeatedly is unwound from one reel and wound onto the other and then reverses direction and unwinds from the other and rewinds on the one, the combination including: a pair of reel gears arranged one in driving relationship with the shaft of one reel and the other in driving relationship with the shaft of the other reel, a reel gear pinion, a pinion arm on one end of which the pinion is rotatably carried, a drive assembly on which the other end of the arm is mounted for rotation through 360° about an axis of arm rotation, a drive gear coaxially disposed for rotation about the arm axis and in driving relationship with the pinion, and a yieldable mounting construction supporting the drive assembly and normally holding the assembly equidistant from each of the reel gears, wherein the distance from said axis of arm rotation to one of the reel gears is slightly less than the distance from said axis to the center of the reel gear pinion plus the pitch radius of the reel gear pinion, and wherein the distance from said axis of arm rotation to one of the reel gears plus the distance of yieldable movement of said yieldable mounting construction is greater than the distance from said axis to the center of the reel gear pinion plus the pitch radius of the reel gear pinion.
